CLAIM

The ornamental design for a display screen or portion thereof with graphical user interface, as shown and described.

DESCRIPTION

The sole FIGURE is a front view of a display screen or portion thereof with graphical user interface, showing the new design.

The dot-dash broken lines in the FIGURE show a display screen or portion thereof and form no part of the claimed design. The remaining broken lines in the FIGURE, including the lined-through text and the evenly spaced broken lines showing an electronic device and portions of the graphical user interface, form no part of the claimed design.
